(57) **CLAIM**

The ornamental design for a fishing float, as shown and described.

DESCRIPTION

FIG. 1 is a front end and right side perspective view of a fishing float which embodies our new and original design therefore;

FIG. 2 is a right side elevational view thereof, the left side elevational view being a mirror image thereof;

FIG. 3 is a top plan view thereof;

FIG. 4 is a bottom plan view thereof;

FIG. 5 is a front end elevational view thereof;

FIG. 6 is a rear end elevational view thereof; and,

FIG. 7 is a rear end and right side perspective view thereof. The broken lines in the drawings represent elements in the environment of the claimed design and form no part of the claimed design.
